UNITED STATES PATENT OFFICE.

GIULIO SILVESTRI, OF VIENNA, AUSTRIA-HUNGARY.

MEANS FOR REGULATING ROTARY PUMPS AND ROTARY ENGINES.

1,141,016.

Specification of Letters Patent.

Patented May 25, 1915.

Application filed June 16, 1913. Serial No. 774,003.

To all whom it may concern:

Be it known that I, GIULIO SILVESTRI, a citizen of Austria, and resident of Vienna, Lower Austria, and Empire of Austria-Hungary, have invented certain new and useful Improvements in Means for Regulating Rotary Pumps and Rotary Engines, of which the following is a specification.

The invention relates to an installation which permits variation at any desired instant and at will, of the quantity of fluid to be delivered by a rotary pump operated at a constant number of revolutions between a maximum determined by the volume of the pump and zero, as is illustrated and described in my copending application Serial No. 774001.

The invention also permits variations at any desired instant of the number of revolutions of a fluid-driven engine receiving its operating fluid from a pump delivering a constant quantity of fluid between the minimum determined by the ratio of volume between pump and engine and a theoretical unlimited maximum, as is illustrated in my copending application Serial No. 774002.

An installation according to the invention includes a rotary distributor or flow interrupter, an automatic valve which, at a certain position of the flow interrupter, causes the liquid to flow in a certain direction, and an accumulator, said parts being connected with the pump or with the engine or with both, and the flow interrupter of which is driven at a rate proportionate to that of the pump or the engine.

The object of the invention is an embodiment of an interrupter which may be used in installations for regulating the output of a pump and also for varying the number of revolutions of a rotary motor.

The flow interrupter forming the object of the invention and in which all of the movable and adjustable parts are completely balanced is shown in Figure 1 in section on line XVI—XVI of Fig. 2 and in Fig. 2 in section on line XVII—XVII of Fig. 1, while Figs. 3 and 4 illustrate in elevation and in section the one half of the sleeve surrounding the distributor.

The casing of the interrupter is in two

parts *a*, of symmetrical form connected to each other in any suitable manner.

As shown, in the interior of each part *a* of the casing are formed a passage *b* and a chamber *c*; each passage *b* communicates with the connecting branch *d* and each chamber *c* with the connecting branch *e*, the said branches *d* and *e* serving according to the direction of rotation, as inlet and outlet 60 for the fluid being delivered. The passages *b* communicate at several points by means of ports *i* with the interior of the casing *a* while the chambers *c* are directly connected with the reduced end of the cavity formed 65 in the casing.

In the casing is mounted the rotary distributor proper indicated at *f*, which is of hollow double conical form and is continuously rotated at a speed proportional to the 70 number of revolutions of the machine or engine controlled thereby; the said distributor being mounted on or forming one piece with a shaft *g* which is led through the stuffing boxes *h* to the exterior of the casing and 75 carries at the outer end the actuating means (not shown).

In the distributor are arranged ports *k*, which, on rotation of the distributor, register with and pass out of register with the 80 ports *i*. The ends of the distributor adjacent the chambers *c* are open so that the interior of the distributor is continuously in communication with the chamber *c*. The distribution of the fluid is therefore always 85 effective when the ports *k* and *i* are in register.

Between the distributor *f* and the casing *a* is fitted a double coned sleeve formed with corresponding ports the size of which determines the duration of the period during which there is a free passage through the ports *k* and *i*. As this duration is to be variable, and accordingly, the length of the ports (considered in the direction of the 95 circumference) must be adjustable, the sleeve is formed of two parts *n* and *o* each part being formed with projections *r* and *s* directed toward one another and engaging each other after the manner of teeth in such 100 manner that in the two extreme positions of the parts in which the pairs of adjacent

edges of the projections are close together, the sleeve has as many ports q as there are ports i in the outer casing a , while in every intermediate position of the two parts 5 double the number of ports q and q^1 is formed in the sleeve, one half of the number (q^1) being covered by solid portions of the wall of the outer casing of the pump and being therefore ineffective.

10 The parts (n) of the sleeve are adjusted and secured immovably within the casing a . The location of one edge of each of the projections r of the part n determines the time of opening of the outlet for the fluid. The 15 middle part o of the sleeve is adapted to be turned and can be manually adjusted by a lever t .

The width of the projections r and s on the two parts of the sleeve is such that when 20 the projections are close together, openings q are formed which are of such length (considered in the direction of rotation) relatively to the ports k in the distributor, that on rotation of the distributor there is no 25 interruption of the flow of the fluid. This result can only be obtained, however, if the number of the ports k on the distributor body, as illustrated, is correspondingly greater than the number of ports in the 30 casing, so that one port k comes into register with the ports q in the sleeve before the preceding port k leaves the same port q in the sleeve.

The formation of the distributor f and 35 the sleeve $n-o$ as symmetrical double cones insures complete balance of these two parts in the axial direction. In addition, the symmetrical formation permits the arrangement of the device for balancing the movable part o of the sleeve in circumferential 40 direction within the apparatus itself. This balancing of the part o of the sleeve in the circumferential direction is effected as follows:

45 In the sleeve o are arranged additional ports w^2 the size of the pressure surfaces of which is chosen with regard to the size of the pressure surfaces of the ports q of the sleeve in such manner, that the turning 50 moment with regard to the central axis of the distributor body is equal; the length of these openings w^2 is about equal to the greatest length of the inlet ports q .

The ports w^2 are engaged by a fixed member 55 x^2 located in a slot in the sleeve o and the length of which member is equal to the length of the plain portions s of the adjustable part o , the length being considered in the direction of the circumference. On 60 placement of the part o of the sleeve the ports w^2 the number of which is equal to the number of ports q are divided together with the ports q into two chambers w^2 and w^4 by means of the member x^2 of which cham-

bers those which have the same angular displacement as the ports for the driving medium, are also under the same pressure as the latter. This is obtained easiest by connecting together the chambers having the same angular displacement; since in these 70 chambers the pressure acts in opposite directions and since the turning moments are equal, the part o of the sleeve is completely balanced and therefore can be displaced without a great amount of force.

75 The distributor f consists preferably of two parts connected by a sleeve f' , and chambers c , are arranged at the sides of the distributor f . The levers t connected to form one piece are led to the exterior 80 through a port u in the casing a .

A flow interrupter of such construction can be used both for pumps and engines, and in this latter case one of the branches intended for the outlet of the fluid may be 85 used for the connection for the delivery part of the pressure pipe, while the other may be used for connection with the accumulator. The apparatus operates in both directions of rotation its parts being 90 completely balanced.

It is evident that the distributor f in place of being rotated may have a reciprocating movement (oscillating movement). To obtain the same effect, this movement however, must extend through an angle of corresponding size.

Having described my invention I declare that what I claim and desire to secure by Letters Patent of the United States is:—

100

1. The herein-described flow interrupter consisting of a casing having four passages two of which serve as driving medium inlets and two as driving medium outlets, a rotary double-conical hollow distributor 105 having a ported wall adapted during its rotation to establish communication at intervals between the driving medium inlets and the driving medium outlets, and a double-conical sleeve disposed between the casing 110 and the distributor, said sleeve consisting of two stationary parts and of an adjustable part intermediate said stationary parts, said parts having interengaging tooth shaped projections and recesses and serving to determine by the length of some of these recesses the duration of the passage of the driving medium through the distributor.

115

2. The herein-described flow interrupter consisting of a casing having four passages two of which serve as driving medium inlets and two as driving medium outlets, a rotary double conical hollow distributor having a ported wall adapted during its rotations to establish communication at intervals between the driving medium inlets and the driving medium outlets and a double conical sleeve disposed between the casing 120

125

and the distributor, said sleeve consisting of two stationary parts and an adjustable part intermediate said stationary parts, said parts having interengaging tooth shaped projections and recesses, said adjustable part being provided with additional openings, said openings being engaged by members fixed within the casing, substantially as and for the purpose set forth.

Signed at Vienna Lower Austria, Austria-Hungary, this third day of June, A. D. 1913.

GIULIO SILVESTRI.
